REAMER

Axel L. Anderson, Rockford, Ill., assignor to Jack & Heintz, Inc., Bedford, Ohio, a corporation of Ohio

Application January 16, 1943, Serial No. 472,579

6 Claims. (Cl. 77—72)

The present invention relates to a novel and improved construction for a reamer or like tool.

It is conventional practice to make reamers with the cutting blades either integral or brazed on the shank. When the blades become too worn for further service it is customary to discard the reamer and use a new one. The object of this invention is to provide an improved reamer with removable blades which may be either replaced or reground when worn. A particular object is to provide a novel construction for removably clamping individual cutting blades on a reamer shank.

The invention is best understood with reference to the accompanying drawings in which:

Figure 1 is a view in side elevation of a reamer constructed according to the principles of the invention;

Figure 2 is an end elevational view of the reamer shown in Figure 1;

Figure 3 is a cross sectional view taken on the line 3—3 of Figure 1;

Figure 4 is a longitudinal sectional view;

Figure 5 is an enlarged view in partial section illustrating the manner in which a removable blade is clamped on the shank;

Figure 6 is an enlarged partial elevational view illustrating the principle of the clamping action; and

Figure 7 is a fragmentary side view of a modified form of the invention.

In the preferred embodiment illustrated the numeral 1 indicates a tubular sleeve constituting the shank of the reamer. The sleeve 1 is provided with an internal shoulder 2 in one end, the other end having an end wall 3 provided with a central depression or opening 4 for a purpose which will later appear. The sleeve 1 is also provided with slots 5 near one end and extending through end wall 3 in the manner shown. In the embodiment shown in Figures 1 to 6 the slot 5 is cut on a diagonal, or spiral, for a purpose which will presently appear. In the other end of sleeve 1 a plug 6 seats against the shoulder 2 and receives the head end of a screw 7. The threaded end of screw 7 engages a sliding bolt 8 guided by a transverse pin 9 riding in slots 10 in the sleeve. The bolt 8 is provided with slots 11 in register with the slots 5 when the bolt is moved nearly to the limit of its movement to the right.

When the slots 5 and 11 are in register, hardened cutting blades 12 may be inserted in the manner shown. Rotation of screw 7 draws the sliding bolt 8 to the left moving slot 11 out of

register with slot 5 and thereby binding the blades 12 firmly in place. Figure 6 illustrates how the slots move out of registry when the bolt 8 slides to the left in the sleeve 1, in the absence of the blades 12. The diagonal arrangement of the slots is such that the sleeve 1 will back up the blades 12 for most effective operation under right hand rotation of the tool in use. This feature is illustrated by the enlarged partial sectional view in Figure 5 looking toward the left in Figures 1 and 4. Tightening of screw 7 has moved bolt 8 and slot 11 longitudinally which has the effect of laterally separating slots 11 and 5 so as to firmly bind a portion 13 of bolt 8 against the front face 18 of blade 12 which is thereby backed up against a portion 14 of sleeve 1. The term "front" face of blade 12 as used herein refers to the cutting side of the blade when rotated in the direction of the arrow in Figure 5. In order to clearly illustrate the above described binding and backing action in Figure 5, spaces 16 and 17 of exaggerated width have been shown where there is no pressure against the blade, as would be the case if the blade were too thin to fill the slots, but it is to be understood that blades 12 are intended to fit the slots without unnecessary looseness so that the spaces 16 and 17 are actually imperceptible. Therefore, the eccentricity of the binding force and reaction does not operate as a couple to produce a tilting or canting of the blade such as might possibly occur if Figure 5 were a scale drawing and the parts were proportioned as therein shown.

Referring to Figure 2, it will be seen that the end of the front face 18 of each blade lies on a radial line with respect to the center of the end wall 3. Where the are an even number of blades these radial lines form common diameters such as the diametral line D in Figure 2. While this particular disposition of the blades is described for purposes of illustrating a preferred embodiment of the invention, it is nevertheless understood that the details of the blade geometry may be varied to best suit the material of the work and the size of the reamer. The number of blades may also be varied, it being within the scope of the invention to use either more or less than four blades.

Where the blades are spaced relatively close together the segments of sleeve 1 lying between the blades are sufficiently resiliently deformable to insure uniform clamping pressures on all the blades. In this manner satisfactory clamping action may be obtained in a large tool by providing

a larger number of blades than would be used on a small tool.

After the blades are securely clamped in place by means of the screw 7 the depression 4 on end wall 3 and a beveled end 22 on sleeve 1 may be used as centers for grinding the blades. After a period of use shims may be placed in the bottoms of the slots and the blades reground, if desired, or the old blades may be replaced with new ones.

The invention thus provides renewable blades for a reamer so that only the blades need be discarded when worn. By avoiding the common method of brazing the blades on the shank, the injurious effects of heat on the blades are removed, insuring better quality tools and allowing greater latitude in the selection of the material of the blades, size of blades and the number of blades.

Figure 7 shows a modification employing blades in slots parallel with the tool axis, primed reference numerals being employed to indicate parts corresponding with those in Figure 1. Thus, the slots 5' and 11' are parallel with the axis of sleeve 1', and slot 10' is angled to cause a slight rotation of the bolt 8' when it is moved longitudinally, to clamp the blades 12' in substantially the same manner as described above in connection with Figures 1-6.

It will be apparent that if it is desired to rotate the tool left handed the slots 5 and 11 in Figure 1, or the slot 10' in Figure 7, may be angled in the reverse directions to back up the cutting blades in the manner described for right hand rotation.

Various changes in the construction and arrangement of parts will occur to those skilled in the art, and all such modifications are included in the invention. The invention is to be limited only by the appended claims and the scope of the prior art.

I claim:

1. A reamer comprising a hollow sleeve, a bolt longitudinally slidable in said sleeve, registering slots in said sleeve and said bolt for receiving removable blade elements, guiding means for said bolt at an angle to said slots to move said slots circumferentially out of registry, and means for sliding said bolt along said guiding means and for securing said bolt, to clamp said blade elements laterally and circumferentially in said slots.

2. A reamer comprising a hollow sleeve, a bolt longitudinally slidable in said sleeve, registering slots in one end of said sleeve and bolt for receiving removable blade elements, a transverse pin through said bolt, a slot in said sleeve at an angle with said blade receiving slots for guiding said pin in a diagonal path with respect to said blade receiving slots, to move said slots relatively laterally out of registry as said bolt moves longitudinally, and a screw in the other end of said sleeve for sliding said bolt to clamp said blade elements laterally and circumferentially in said registering slots.

3. A reamer comprising a hollow sleeve, a bolt longitudinally slidable in said sleeve, registering

slots in one end of said sleeve and bolt for receiving removable blade elements, guiding means for said bolt disposed in a diagonal path with respect to said registering slots to move said slots relatively laterally out of registry as said bolt moves longitudinally, the other end of said bolt having a screw threaded portion, an internal shoulder in the other end of said sleeve, a plug seated against said shoulder, and a screw having a head seating in said plug and a threaded portion engaging said bolt to draw said bolt through said sleeve and laterally and circumferentially clamp said blade elements in said registering slots.

4. A reamer comprising a hollow sleeve, a bolt longitudinally slidable in said sleeve, registering slots in one end of said sleeve and bolt for receiving removable blade elements, a transverse pin through said bolt, a slot in said sleeve for guiding said pin in a diagonal path with respect to said registering slots, the other end of said bolt having a screw threaded portion, an internal shoulder in the other end of said sleeve, a plug seated against said shoulder, a screw having a head seating in said plug and a threaded portion engaging said bolt to draw said bolt through said sleeve and move the slots in said bolt circumferentially out of registry with the slots in said sleeve to clamp said blade elements therebetween and machine centers formed on the ends of said sleeve for use in grinding said blades.

5. A reamer comprising a hollow sleeve, diagonal slots in one end of said sleeve for receiving removable blade elements, a bolt slidable in said sleeve having blade receiving slots registering with said first mentioned slots, a guide pin in said bolt, an axially directed slot in said sleeve for guiding said pin for non-rotative longitudinal movement of said pin and said bolt at an angle to the directions of said slots to move said slots relatively laterally out of registry as said bolt moves longitudinally, and elements on said bolt adapted to laterally and circumferentially clamp said blade elements in said diagonal slots upon said movement of said bolt.

6. A reamer comprising a hollow sleeve adapted for rotation in a predetermined direction in a reaming operation, slots in said sleeve for receiving blade elements, a bolt within said sleeve having blade receiving slots registering with said first mentioned slots, means to move said bolt longitudinally in said sleeve and to secure said bolt when so moved, and means to guide the direction of said movement of said bolt at an angle to the directions of said slots to move said slots relatively laterally out of registry as said bolt moves longitudinally so that said slots in said bolt will laterally and circumferentially bind said blade elements on their front sides with respect to said direction of rotation and said slots in said sleeve will back up said blades on their back sides against the forces transmitted thereto in said reaming operation.

AXEL L. ANDERSON.
